CURL REMOVER

Robert M. Ingham, Jr., Spartanburg, S.C., assignor to Deering Milliken Research Corporation, Pendleton, S.C., a corporation of Delaware

Application August 21, 1957, Serial No. 679,480

20 Claims. (Cl. 57—54)

This invention relates to a novel arrangement for aiding in the removal of yarn curls formed about the base of a rotatable spindle.

In the art of winding yarn onto bobbins or other yarn carriers supported on spinning or twisting spindles or the like, one present practice is to spin a few turns of yarn onto the spindle proper immediately below the lower end of the yarn carrier, such as a bobbin, at the conclusion of winding of the yarn package onto the bobbin in order to provide for continuation of the yarn onto the next empty bobbin to be donned onto the spindle after doffing of the full bobbin. The doffing of the full package thus leaves few turns of yarn on the spindle, and upon the placing of a new empty bobbin onto the spindle the yarn is then wound from this starting point around the bobbin, thus leaving the several turns, which may be called curls wrapped around the spindle. If these curls are not removed periodically they will accumulate to the point of forming a large mass which is quite troublesome and often requires the shutdown of the entire frame in order to clean the spindles and obtain proper operation thereof. While attempts have been made in the past to solve this problem, to my knowledge none of these attempts have been entirely satisfactory.

Accordingly it is a major feature of this invention to provide an arrangement for removing, or aiding in the removal of, the curls or turns formed on spindles or the like beneath the lower end of the bobbin or other carrier.

A further feature of this invention is to provide a curl remover for spindles, which is operable either at a selected time after the beginning of the spinning, twisting or winding operation either manually by the operator or at a substantially predetermined time thereafter automatically.

Still a further feature is to provide a curl removing arrangement for spindles and the like which is deactuated by the operation of the ring rail or other analogous part of the apparatus at the end of each package formation cycle.

Still other features and many attendant advantages of the invention will become apparent to one skilled in the art from a reading of the following detailed description of several embodiments according to the invention, taken in conjunction with the accompanying drawings wherein:

Figure 1 is a schematic illustration in partial section of one embodiment constructed in accordance with the invention.

Figure 2 is a schematic illustration in partial section showing the curl remover in operative curl removing position.

Figure 3 is a fragmentary view of the yarn severing member of Figures 1 and 2.

Figure 4 is an illustration in partial section of a modified embodiment of the invention.

Figure 5 is a schematic illustration in partial section

2

of another modified embodiment according to a further aspect of the invention.

Figure 6 is a fragmentary view of the modified yarn severing member employed in the embodiment of Figure 5.

Figure 7 is a schematic illustration in front elevation of a plurality of spindle positions arranged according to the embodiment of Figure 5.

Figure 8 is a schematic side illustration in partial section of a further embodiment according to the invention.

Referring to Figure 1, the invention is shown as applied to a conventional spinning arrangement employing a ring rail 11 having a ring holder 13, ring 15, and traveler 17, within which ring is concentrically mounted a spindle 19 which may be rotatably driven through means of a belt, not shown, engaging a whorl 23, formed at the lower end of the spindle. The spindle may be rotatably mounted in any conventional or desired manner on a spindle rail 25, as through the use of a bolster arrangement 27.

The spindle 19 has a neck portion 21 formed immediately above the whorl 23 which is preferably of straight cylindrical form, although such may be tapered if desired provided the cutter axis is then mounted parallel to the taper. A bobbin 29, having a spacer sleeve 31, of rubber, plastic or other suitable material, formed on its lower open end, is removably fitted onto the spindle with its lower end portion extending down over the cylindrical neck 21 of the spindle. The bobbin is preferably of the top drive type, but may be driven through the medium of the sleeve 31, or otherwise, if desired. By virtue of the sleeve 31 the lower end of the bobbin is separated from the periphery of the neck 21 to form a small annular space.

A yarn severing member is movably mounted on the spindle rail 25, and preferably takes the form of a cutter 33 which is formed or secured to an arm 35 fixedly mounted on the plunger rod 39 of a dashpot arrangement 37 which may be suitably mounted as by securing screws, welding, or otherwise as desired, on the outer side of the spindle rail 25. In the illustrated and preferred example the cutter 33 takes the form of a flat arcuate blade extending in the longitudinal direction of the spindle axis and having its cutting surface extending along a longitudinal edge thereof. The arm 35 may be mounted for adjustment longitudinally of the plunger as through the use of a set screw 41.

In the illustrated example the dashpot arrangement comprises a cylinder 43 having plunger 45 reciprocably mounted therein, the plunger having a plunger rod 39 of square or other non-circular cross-section to prevent angular displacement thereof. The plunger 45 is resiliently biased upwardly as by a compression spring 47. An adjustable air valve 49, of conventional construction, is provided in the lower end of the cylinder 43. Adjustment of valve 49 determines the rate of return travel of the plunger 45 in the upward direction, and is thus a determining factor in the time delay which occurs between the beginning of each winding cycle and the time when the curls are severed. The yarn severing member 33 is arranged closely adjacent, but preferably not touching, the neck 21 of spindle 19. In the uppermost position of the plunger 45 the arm 35 is preferably slightly beneath the lower edge of the bobbin 29 with the severing member or portion 33 thereon being preferably within the space formed between the bobbin and the neck 21, as shown in Figure 2. In the lowermost position of the severing member and plunger, the severing member is completely out of operative relation in respect of the bobbin 29 and is beneath the lowermost doffing curl to be formed on the neck 21 of the spindle, as shown in Figure 1.

70

For the purpose of describing the operation of this apparatus let it be assumed that a full bobbin has just been completed. In this position the ring rail will have been lowered to a position with the ring 15 and traveler 17 beneath the lower end of the bobbin 29 so as to form the doffing curls C. At this time and by this action the ring rail (or some part thereon, such as ring holder 13) will have engaged the plunger rod 39 to which the cutter is connected and will have lowered the cutter to its inoperative position. In this position the cutter is beneath the lowermost curl formed by the traveler 17. The full package is doffed, leaving the doffing curls C on the neck 21 of the spindle, as shown in Figure 1.

Upon the movement of the ring rail upwardly to begin the regular traversing stroke along the longitudinal length of the bobbin 29, the cutter 33 will begin a gradual upward movement along the neck 21 of the spindle under the action of the spring 47 in the dashpot arrangement 37. After a predetermined period of time, determined by the adjustment of valve 49, the cutter 33 will reach the position shown in Figure 2 and will cause the yarn connection between the curls C and the yarn on the bobbin 29 to be severed. It will be apparent that the most advantageous action in this instance will be a cutting action; however, it is within the scope of the invention to employ a breaking action at this point, and thus an element other than a cutter 33 may be employed to break the yarn at this point since the breaking action occurs by virtue of the rotation of the bobbin 29 and spindle 19 bringing the yarn directly and forcibly into engagement with the cutter which is extending within the space formed between the neck 21 and the lower end of bobbin 29. The severed curls C which are now loose upon the neck 21 fly off in the usual case substantially immediately from the neck 21 by virtue of the rotation of the spindle 19 and due largely to centrifugal force and air resistance. In the event that such are not removed automatically at some point during the winding of the bobbin from which they are severed, they will substantially always fly off at least during the winding of the next or one of the next few succeeding bobbins, although in some very few instances manual removal by the operator may be necessary. This latter is not the usual case, however, the normal and usual operation being a substantially immediate self-removal of the curls through the continued rotation of the spindle 19. The cutter may be left in this upper position for the entire remainder of the winding process for forming the package on the bobbin 29, if so desired. At the conclusion of the winding cycle, the ring rail 11 is lowered to the position shown in Figure 1, whereupon the cutter 33 is lowered beneath the lowermost of the doffing curls as mentioned above. The cycle of operations may then be repeated, and such may be repeated as often as desired.

In Figure 4, an arrangement similar to that of Figures 1-3 is shown, but incorporating a simpler and preferred dashpot and mounting arrangement therefor. In this modification the dashpot 50 has a molded body cylinder 51 of plastic, metal, or the like which is removably secured to a mounting bracket plate 53 as through the medium of securing screws 55. Bracket plate 53 has a laterally offset aperture 57 therein which encircles in complementary relation the spindle supporting base 59 which is of standard construction. In the illustrated example the bracket plate 53 is secured between a rubber washer and the spindle rail 25.

The severing member 33' and offset arm 35' is laterally adjustably secured in a transverse slot in plunger 61 as by a set screw 63. Adjustment of rate of upward movement of the plunger 61 is accomplished by adjustment of a screw 65, and washers 67 of felt or similar air-permeable filter material serve to keep foreign particles such as dust, lint, etc., out of the air passageway formed between the threads of the tapped hole in the plate 53 and the threads on screw 65.

A modification, in which the actuation of the cutter may be manually accomplished, is illustrated in Figure 5, although such may also be constructed for automatic actuation if so desired. In this arrangement the cutter 69 is formed integrally with offset arm 71 as by suitably machining or forming the radially inner end of the arm to effect a cutting end slightly upturned, although the cutter may be identical to the cutter 33 of Figure 1, if desired. The arm 71 is secured, as by a set screw 73, to a bar 75 which is slidably reciprocably mounted within in a bracket 77 suitably secured to the front side of the spindle rail 25. The bar 75 has a pin 79 extending therethrough with a thrust washer 81 in engagement therewith. A compression spring 83 is mounted in surrounding relation about the bar and extends between the washer 81 and the bottom wall of the bracket 77. The bar 75 has adjustably secured at its lower end, as by a set screw 85, a three-quarter collar 87 for the purpose of forming a stop to determine the upper or released position of the cutter 69.

A spring latch 89 is mounted on the outermost side of the front or outer wall of bracket 77 and engages with a notch 91 formed in the adjacent side of the bar 75. The spring latch serves to retain the cutter in its cocked position against the action of the spring 83 until such time as it is desired to release the severing member and permit it to move into severing position adjacent the lower edge of the bobbin 29. This release may be accomplished either manually or automatically through the action of a release bar 93 extending laterally between the spring latch 89 and the adjacent outer face of the bracket 77. Movement of the release bar 93 laterally and/or angularly so as to move the spring latch 89 laterally outwardly effects release of the latch from the notch 91 and thus permits the compression spring 83 to move the bar 75 and severing member 69, 71 immediately upward into yarn severing position at the lower edge of the bobbin 29. As stated, this action may take place through automatic apparatus or may be accomplished manually by an operator, and in either case, such may be accomplished at any desired time after the package has begun to be formed on the bobbin 29.

It will be apparent that the release bar 93 may be a long bar pivotally supported on the spinning frame as indicated at 95 and which extends through a plurality of spring latches for a corresponding plurality of spindle positions, as shown for instance in Figures 5 and 7, whereby lateral pivotal movement of the release bar, as by movement of handle 97, will simultaneously release the yarn severing member for each of the spindle positions.

The lowering or "cocking" of the yarn severing member 69, 71 is similar to the cocking of the cutter of the first embodiment. As in the first embodiment the ring rail 55 is lowered at the end of the package winding cycle to a point beneath the lower end of the bobbin 29 at the conclusion of the winding of the package onto the bobbin. During this time the cutter 69 is lowered through the engagement of a portion of the ring rail, such as the ring holder 13, with the bar 75, and the curls C are formed on the neck 21 of the spindle. At the lowermost position of the ring rail the spring latch 89 engages the notch 91, thus locking the cutter 69 in its lowermost position. The subsequent movement of the ring rail 11 in its traversing stroke along the length of the newly donned bobbin 29 may then be accomplished in the usual manner, with the cutter being retained in its lowermost position until such time as it is desired to actuate the same for cutting of the connection between the curls C and the package being wound on the bobbin 29.

While it is most desirable to employ a straight neck 21 for the spindle 19 in order to permit the cutter to move in close adjacency to the neck and along a straight path parallel to the axis of the spindle, it is feasible to provide a tapered or other shaped spindle neck for holding

of the curls C, in which case the movement of the cutter may be altered to accommodate the particular configuration of the neck. For example, in the case of a tapered neck the cutter might be made to move along an oblique line from an outermost position upwardly and toward the axis of the spindle. It will be noted that it is not necessary for the cutter to completely follow the configuration of the neck but normally it is desirable to assure that the cutter does not materially engage the neck at any point along its travel so as to cut or mar the neck of the spindle or break the cutter. It may sometimes be feasible, however, to have the cutter actually come into contact with the neck either in a part or along the whole length of travel, although it is normally most desirable that such not be the case, particularly in order to provide for most advantageous function and longer life of the various parts. The same is true for the relation of the cutter to the lower edge of the bobbin, wherein the supporting arm upper surface adjacent the cutter may be allowed to engage the lower edge of the bobbin as may the cutter itself engage the bobbin and/or the neck of the spindle between the neck and the bobbin in the annular space therebetween. For the proper operation of the device, however, it is not necessary that any engagement of these parts take place, as the severing action will occur through the engagement of the cutter or severing member 33 (or 69, Figure 5) with the yarn extending between the bobbin and the curls C.

While the preferred and most advantageous arrangement employs a bobbin and spindle relation wherein a clear annular space is formed between the lower edge of the bobbin and the neck of the spindle, it is not absolutely necessary that such be constructed in this manner, as for instance the cutter may be made to engage and sever progressively the several yarn curls as it moves longitudinally of the spindle. For such a mode of operation a yarn severing member similar to that of Figure 5 would be advantageous, or other suitable configurations might be employed as desired.

Although the above illustrated examples utilize the ring rail as the "cocking" medium for the reciprocable yarn severing members, it will be appreciated that other elements of the frame may be employed to effect this function. For instance, the conventional reciprocably moving thread board or its moving mechanism, may be adapted to "cock" or deactivate the severing element or elements; or other elements designed particularly for this purpose might be employed, if desired. However, it will be apparent that the utilization of existing elements insofar as possible is the most highly advantageous arrangement in most instances, and such is therefore the preferred mode of practice of the invention.

In a further embodiment according to the invention, as illustrated in Figure 8, the curl severing member is moved into curl-severing position by the movement of one or more of the conventional reciprocably driven members of a standard spinning or twister frame, in the present instance the movement-imparting member being the thread board lifter rod or rods 99. Mounted on the longitudinally spaced thread board lifter rods 99 is a channel member 101 running behind and parallel to the spindle rail 25. The channel member 101 is free to slide with vertical motion relative to the lifter rods and is supported in operative position thereon by a collar 103 on each lifter rod, which collars are suitably adjustably fixed on the rods 99 as by set screws 105. Preferably, a compression spring 107 may be provided between each collar 103 and the channel 101, together with a positive upper stop 109, which stop 109 may be vertically adjustable in any desired manner. The advantage of the employment of the spring 107 lies in the fact that the cutting or severing action by the severing member may be continued over a longer portion of the build, using the resilience of the spring to permit cyclic increasing of the height of the collars 103 by the push rods with no increase in

the top height of the severing members 111, 113, and thus no interference with the bobbins 29 on the spindles 19.

Secured to the channel member 101 at each spindle 19 is a cutter support leg 111 which in the instant example extends forward to the spindle rail 25 and then angles upwardly directly behind the spindle 19 and to about $\frac{1}{16}$ inch above the top side of the whorl 23. A cutter 113 is secured to the upper end of the leg 111 as in the previous examples. The bottom position of the cutter assembly 101, 111, 113, is set by the support legs 111 resting on the spindle rail 25, and the whole cutter assembly remains at this position until near the end of the spinning cycle (for filling and combination winds) when the frame builder motion will have raised the thread board lifter rods 99 to or near their maximum height, as through the medium of the conventional lifter rod arm 115 and shoe 117, and the yarn has practically filled the bobbin. In warp wind builds this upper position of the lifter rods 99 may occur periodically a number of times during the course of the wind; however, only the first occurrence is normally necessary to effect complete severance. At this upper position of the lifter rods, the collars 103 will have raised the channel member 101 and severing members 111, 113 into curl severing position as described in connection with the previously described embodiments. Thus each cutter 113 will be raised to extend between the bobbin bottom ferrule and the spindle 19, and continued rotation of the spindle effects severing of the yarn between the doffing curls and the bobbin, freeing the curls which then fly off the spindles as previously described, leaving the spindles bare and ready for the next doff.

It will be apparent that various other modifications and alternatives may be employed within the scope and spirit of the invention, and that the above described embodiments are merely given for the purpose of illustration. Accordingly it will be understood that the invention is not to be limited by the specific illustrated embodiments described herein, but only by the scope of the appended claims.

What is claimed is:

1. In combination, a support, a spindle rotatably mounted on said support and adapted to receive a yarn carrier having an open base end, a traversing member reciprocable longitudinally of said spindle, a yarn severing member rotatably free of said spindle and reciprocably mounted adjacent the base of said spindle for movement substantially longitudinally of said spindle, and means for moving said severing member longitudinally toward the normal position for said open base end of a yarn carrier as normally mounted on said spindle.

2. In combination, a support, a spindle rotatably mounted on said support and adapted to receive a yarn carrier having an open base end, a traversing member reciprocable longitudinally of said spindle, a yarn severing member reciprocably mounted adjacent the base of said spindle for movement substantially longitudinally of said spindle, and means for moving said severing member longitudinally toward the normal position for said open base end of a yarn carrier as normally mounted on said spindle, said traversing member being engageable with said severing member to a point past the normal traversing stroke of said traversing member to render said severing member inoperative.

3. The combination according to claim 1 wherein said spindle base is of substantially straight cylindrical external configuration along the path of said yarn severing member, said yarn severing member being movable along a path substantially parallel with the longitudinal surface of the adjacent portion of said path.

4. In combination, a support, a spindle rotatably mounted on said support and adapted to receive a yarn carrier having an open base end, a traversing member reciprocable longitudinally of said spindle, a yarn sever-

ing member reciprocably mounted adjacent the base of said spindle for movement substantially longitudinally of said spindle, and means for moving said severing member longitudinally toward the normal position for said open base end of a yarn carrier as normally mounted on said spindle, a bobbin having an open base end and adapted to be mounted on said spindle, said lower base end of said bobbin being of larger internal diameter than the adjacent outer diameter of said spindle base with the bobbin fully sealed on said spindle, whereby 10 an annular open space is formed between said spindle base and the base end of said bobbin, and a spacer member between said bobbin and said spindle and longitudinally spaced from the base end of said bobbin, said severing member having a portion thereof adapted to extend into said annular open space to effect severing action on a yarn curl extending between said spindle base and the exterior of said bobbin.

5. The combination according to claim 1, wherein said last named means includes a rod movable longitudinally of said spindle and operatively connected to said severing member.

6. In combination, a support, a spindle rotatably mounted on said support and adapted to receive a yarn carrier having an open base end, a traversing member reciprocable longitudinally of said spindle, a yarn severing member reciprocably mounted adjacent the base of said spindle for movement substantially longitudinally of said spindle, and means for moving said severing member longitudinally toward the normal position for said open base end of a yarn carrier as normally mounted on said spindle, said last named means includes a rod 20 movable longitudinally of said spindle and operatively connected to said severing member, a resilient spring connection resiliently biasing said rod and said severing member longitudinally of said spindle, and a stop adapted to limit movement of said severing member in a direction toward said open base end of said yarn carrier.

7. The combination according to claim 6, wherein said rod is a thread board lifter rod, and means for moving said rod during rotation of said spindle.

8. In combination, a support, a spindle rotatably mounted on said support and adapted to receive a yarn carrier having an open base end, a traversing member reciprocable longitudinally of said spindle, a yarn severing member reciprocably mounted adjacent the base of said spindle for movement substantially longitudinally of said spindle, and means for moving said severing member longitudinally toward the normal position for said open base end of a yarn carrier as normally mounted on said spindle, a dashpot having a plunger, and spring means biasing said plunger longitudinally in the direction of the free end of said spindle, said severing member being carried by said plunger.

9. The combination according to claim 8, wherein said dashpot has a threaded valve adjusting means, and a filter associated with said adjusting means and adapted to prevent the entry of lint, dust, or the like therein.

10. The combination according to claim 1, further comprising a bracket plate having an aperture therein and surrounding said spindle, said yarn severing member and means for moving said severing member being mounted on said bracket plate laterally of said support, said bracket plate being removably secured to said support.

11. In combination, a support, a spindle rotatably mounted on said support and adapted to receive a yarn carrier having an open base end, a traversing member reciprocable longitudinally of said spindle, a yarn severing member reciprocably mounted adjacent the base of said spindle for movement substantially longitudinally of said spindle, and means for moving said severing member

longitudinally toward the normal position for said open base end of a yarn carrier as normally mounted on said spindle, resilient means resiliently biasing said severing member longitudinally of said spindle toward said bobbin base, and means tending to restrain the movement of said severing member toward said bobbin base.

12. The combination according to claim 11 wherein said restraining means is a positively acting lock, and means adapted to release said lock.

13. The combination according to claim 12 including a plurality of said spindles, yarn severing members, severing member moving means and locks, said lock releasing means being common to all of said locks.

14. In combination a support, a spindle rotatably mounted on said support and adapted to receive a bobbin, a bobbin adapted to be fitted onto said spindle and having an open base end, a yarn severing member movably mounted adjacent the supported end of said spindle, a spring operatively associated with said severing member and tending to move said severing member toward said base end of said bobbin, said severing member being movable longitudinally along said supported end of said spindle, and means adapted to move said severing member against the action of said spring and away from said open base end of said bobbin.

15. The combination according to claim 14 further comprising a ring rail, said ring rail being normally out of operative association with said severing member, said ring rail having a part thereon selectively movable into operative relation with said severing member to move said severing member away from said base end of said bobbin.

16. The combination according to claim 14 wherein said severing member is a cutting blade disposed with its cutting edge extending longitudinally of said spindle and substantially tangential to a circle having the axis of said spindle as a center.

17. The combination according to claim 14 further comprising a slidably movable non-circular member, said severing member being adjustably secured to said slidably movable member in laterally offset relation therefrom, and means forming a guide slot for guiding the motion of said slidably movable member.

18. The combination according to claim 14 wherein the yarn severing portion of said severing member is laterally offset from the path of movement of said spring.

19. In combination a support, a spindle rotatably mounted on said support and having an outwardly extending free end over which a bobbin is adapted to be fitted, a yarn severing member movably mounted for longitudinal movement along the base end of said spindle, resilient means operatively associated with said severing member and tending to move said severing member in a direction toward said free end of said spindle, and means adapted to move said severing member against the action of said resilient means in a direction away from said free end of said spindle and to an inoperative position.

20. The method of removing curls formed on a spindle neck and connecting between the neck of the spindle and a bobbin on said spindle, comprising severing the yarn connection between said curls and the yarn on said bobbin while said spindle is running, said severing being effected beneath the lower end of said bobbin and between the circumferential periphery of the base of said bobbin and the adjacent neck portion of said spindle.
